UNITED STATES PATENT OFFICE

152,652

DESIGN FOR A STROLLER BODY

Frederick T. Regan, Brookville, Mass., assignor to
Hedstrom-Union Company, Fitchburg, Mass., a
corporation of Massachusetts

Application April 22, 1948, Serial No. 145,893

Term of patent 14 years

(Cl. D14—14)

To all whom it may concern:

Be it known that I, Frederick T. Regan, a citizen of the United States, residing in Brookville, in the county of Norfolk and State of Massachusetts, have invented a new, original, and ornamental Design for a Stroller Body, of which the following is a specification, reference being had to the accompanying drawing, forming part thereof.

In the drawing:

Figure 1 is a perspective view of a stroller body, showing my new design, the body being mounted on a conventional chassis which is shown in dotted outline, for illustrative purposes only, and the design of both sides of the body being substantially the same.

Figure 2 is a rear elevation of the stroller body of Fig. 1.

I claim:
The ornamental design for a stroller body, as shown and described.

FREDERICK T. REGAN.
